A. CLAWSON,
FOLDING OR COLLAPSIBLE RECEPTACLE.
APPLICATION FILED MAY 21, 1917.

1,256,112.

Patented Feb. 12, 1918.

UNITED STATES PATENT OFFICE.

ARCHIE CLAWSON, OF ROCKVALE, MONTANA.

FOLDING OR COLLAPSIBLE RECEPTACLE.

1,256,112.

Specification of Letters Patent. Patented Feb. 12, 1918.

Application filed May 21, 1917. Serial No. 169,979.

To all whom it may concern:

Be it known that I, ARCHIE CLAWSON, a citizen of the United States, residing at Rockvale, in the county of Carbon and State of Montana, have invented certain new and useful Improvements in Folding or Collapsible Receptacles, of which the following is a specification, reference being had to the accompanying drawings.

10 This invention relates to certain improvements in folding or collapsible boxes, crates, and similar receptacles such, for instance, as that shown and described in my prior application for patent, filed April 7, 1917, Serial Number 160,442.

It is the primary purpose of the present invention to provide improved means for quickly and securely fastening the top of the box in position when the box is either open or collapsed.

It is a more particular object of the invention to provide vertical corner brackets fixed to the bottom and side sections of the box, and latch devices on the ends of the box top for detachable engagement with the brackets on one of the side sections when the box is open and for engagement with certain of the corner brackets on the box bottom when the box is closed or collapsed, the box top in the latter position fitting between said corner brackets whereby it is held against shifting movement.

It is an additional object of my invention to provide improvements in folding boxes or crates as above characterized, whereby such devices are rendered highly serviceable and convenient in practical use, and without increasing the manufacturing cost of my original invention, above referred to.

With the above and other objects in view, my invention consists in the novel features of construction, combination, and arrangement of parts to be hereinafter more fully described, claimed and illustrated in the accompanying drawings, in which,

Figure 1 is a side elevation looking at the front of the box when the same is set up;

Fig. 2 is a fragmentary plan view;

Fig. 3 is an end elevation;

Fig. 4 is a fragmentary elevation similar to Fig. 1, the box being folded or collapsed;

Fig. 5 is an end elevation of the box folded;

Fig. 6 is a detail perspective view of the 55 shiftable latch plate;

Figs. 7 and 8 are detail perspective views of the corner brackets secured to the bottom and sides respectively of the box; and

Fig. 9 is an enlarged longitudinal section of one of the fasteners for the box top.

Referring in detail to the drawings, 5 designates the bottom of the box, to the corners of which the angular, upstanding 65 brackets 6 are secured. These brackets are similar to those shown in my prior application, but are of the same height. The vertical flanges of said brackets extending longitudinally of the box bottom, are provided in their upper ends with the slots 7. The sides 8 and the ends 9 of the box or 70 crate are pivotally mounted at their lower edges upon the flanges of the corner brackets 6 disposed inwardly upon the box body 75 in the usual manner.

10 designates the top of the box which is adapted to be detachably fastened or secured against movement relative to the other elements of the box structure either when the same is set up or when it is folded or collapsed. To the ends of each side section 8 of the box, the metal bracket plates 11 are secured, said plates likewise being of angular form and the flanges thereof extending above the upper edge of the box section 8. The bracket flange which extends longitudinally of said box section is provided adjacent its upper edge with a slot 12.

Upon the top 10 of the box, at each end thereof and adjacent one of its longitudinal edges, the metal straps 13 are securely fixed, said straps at one of their ends projecting beyond the longitudinal edge of the box top and being formed with terminal hooks 14 which are adapted for engagement through the slots 12 in one pair of corner brackets 11 when the box is set up, or in the slots 7 of one pair of bracket members 6 when the box is collapsed or folded. A latch plate 15 is also mounted upon each end of the box top 10 and is shiftable transversely thereof. This latch plate is movable through spaced keeper straps 16, the

ends of which are suitably secured to the box top, and each latch plate is provided upon its inner end with an upstanding lug 17 to limit the sliding movement of the plate in one direction. Each plate 15 is also provided with an elongated opening 18 between the keeper straps 16, and to said plate, at one end of the opening 18, the end of a leaf spring 19 is riveted or 10 otherwise securely fixed. A metal plate 20 is riveted upon the under side of this leaf spring and is provided upon one end with an angular lug 21. The spring 19 normally acts to retain the plate 20 within the opening 18 and in the plane of the latch plate.

In the use of the present invention, when it is desired to use the box, the sides and ends are disposed in erect positions and held against relative movement by any suitable 20 means. The box top 10 is then arranged in position, the terminal hooks 14 on the metal straps 13 being engaged through the openings 12 in one pair of the bracket members 11. The plate 20 is then raised by pulling upwardly upon the lug 21 thereof and the latch plate 15 on each end of the box is forced outwardly so as to dispose the terminal hook 22 formed on the outer end of said plate in spaced relation to the longitudinal 30 edge of the box top. The top is then lowered into position upon the upper edges of the side and end sections of the box between the bracket members 11. The latch plates 15 are then forced inwardly so as to engage 35 the hooks 22 thereon in the openings 12 of the other pair of brackets 11. The spring-pressed plates 20 will ride over the outermost keeper straps 16 and when the hooks 22 are disposed through the openings 12, the 40 lugs 21 on the plates 20 will snap behind said keeper straps, said plate fitting within the opening 18 in the latch plate as above described. Thus, the casual outward shifting movement of the latch plate 15 is effectually prevented so that the box top 10 is 45 securely held in position.

In folding or collapsing the box, the end sections are first folded inwardly upon the box bottom and then the box sections folded 50 in superposed relation upon said end sections. The top 10 is then arranged in position upon the uppermost side section, the terminal hooks 14 on the straps 13 being engaged through the slots 7 in one pair of 55 the brackets 6 and the hooks 22 of the shiftable latch plates engaged through the openings in the other pair of corner brackets 6 in identically the same manner as above referred to, in the locking of the box top when 60 the box is assembled in condition for use. The corners of the box top fit snugly between the flanges of the brackets 6 so that said box top is held against all possibility 65 of shifting movement and strain upon the shiftable latch elements and their possible

release from engagement with the bracket flanges, is obviated. As the plates 20, when in normal position, are disposed in the plane of the latch plates 15 and the lugs 17 and 21 are very short, the possibility of the 70 spring-held plate 20 being accidentally struck and displaced so as to permit of the shifting movement of the latch plate, is reduced to a minimum.

From the foregoing description, taken in 75 connection with the accompanying drawings, the construction, manner of operation and several advantages of the present invention will be clearly and fully understood. While I have illustrated in the drawing a 80 certain construction of the box, it is manifest that the fastening means for the box top is applicable to various other constructions of collapsible or foldable boxes or crates. The devices may be advantageously 85 used upon crates or boxes employed for the shipment of chickens, eggs, bread, and like commodities. By means of my improved fastener, the several parts of the box will be very rigidly held either in their erect positions or in their compacted or folded positions. The device is also quite simple and inexpensive in its construction and manifestly of great durability.

While I have herein shown and described 95 the preferred construction and arrangement of the parts employed, it is to be understood that I reserve the privilege of adopting all such legitimate changes as may be fairly embodied within the spirit and scope of the 100 invention as claimed.

Having thus fully described my invention, what I desire to claim and secure by Letters Patent is:

1. The combination with a box having a 105 removable top, of a bracket secured to a part of the box structure and having a slot therein, a shiftable latch plate mounted upon the box top, spaced guide straps for said latch plate secured to the box top, said plate 110 having a hook on one end for engagement in the slot of said bracket, said plate being further provided with an opening, and a spring held member engaging in said opening and having a part projecting above the 115 surface of the latch plate to coact with one of the guide straps and prevent shifting movement of the latch element from its locking position.

2. The combination with a folding box 120 having a removable top, of brackets secured to one part of the box structure, each bracket being provided with a slot, shiftable latch plates on the box top, spaced guide straps for said latch plates secured to the box top, 125 each of said latch plates having a hook on one end for engagement in the slot of one of the brackets, each latch plate being further provided with an opening, a leaf spring fixed to the plate at one end of the opening, 130

and a plate secured to the under side of said spring and normally disposed within said opening in the plane of the latch plate, said latter plate being provided with a lug on one end to co-act with one of said guide straps and prevent shifting movement of the latch plate from its locking position.

In testimony whereof I hereunto affix my signature in the presence of two witnesses.

ARCHIE CLAWSON.
